UNITED STATES PATENT OFFICE

1,939,702

MACHINE FOR PRODUCING JUSTIFIED GROUPS OF IMPRESSIONS

Henry Beetle Hough, Martha's Vineyard, Mass.

Application May 16, 1931. Serial No. 537,921

31 Claims. (Cl. 199—71)

This invention relates to machines for producing impressions of characters arranged in groups spaced apart over a predetermined space on an impression receiving element so as to fill the space accurately and completely. More particularly the invention relates to machines for casting lines of type.

Line casting machines, such as linotype, inter-type and linograph, require the circulation of a plurality of matrices through a phase of assembly, a phase of casting, and a phase of distribution in which they are returned to the magazine. This circulation of matrices makes necessary the provision of a machine of complex design and makes impossible the construction of a machine of small size. Unless the machine receives constant expert attention satisfactory operation is unlikely. The matrices may stick at various places in their cycle; they may transpose as they are assembled; or they may fail to distribute properly causing so-called "distributor stops" which are a common source of lost time. The matrices are frequently damaged and must be replaced. Since they are not secured in the machine in any way they may be forced out and drop to the floor. The continuous circulation of a large number of small matrices, each independent of the others, involves difficulties which cannot be entirely overcome. Inherent in the principles underlying the construction of prior machines of this type are a number of such difficulties and a number of obvious limitations.

What is true of the matrices in the existing machines is also true of the space bands. Being separate they may jamb, fall out, fail to drop into proper position or two may fall at a time. They may fail to return to the space band box requiring the time and attention of the operator.

In the operation of these prior machines, the operator must do a great deal of hand spacing since it is impossible to cause the justification of lines through the action of space bands when the space left in the line is more than a certain maximum. The space which the space bands will take up depends upon the number of bands in the line and this is dependent upon the judgment of the operator. An operator of these prior machines must have considerable training before acquiring facility. The operation depends so much upon the skill of the operator that many individuals can never hope to be successful.

It is the object of the present invention to overcome these difficulties and provide a machine of simpler construction embodying principles applicable in the construction of ma-

chines for producing any justified line of impressions or group of impressions such, for example, as a justifying typewriter or embossing machine, as well as a line casting machine.

The invention will be more clearly understood from the following description in conjunction with the accompanying drawings, in which,

Fig. 1 is a longitudinal vertical sectional view of a machine embodying the invention and with certain of the parts broken away.

Fig. 2 is a plan view with part of the casing broken away.

Figs. 3 and 4 are vertical sections taken on the lines 3—3 and 4—4 respectively of Fig. 1.

Fig. 5 is a fragmentary front elevational view of the same.

Fig. 6 is a plan view of a pattern forming part of the machine showing the parts thereof in their normal positions.

Fig. 7 is a sectional view taken upon the line 7—7 of Fig. 6.

Fig. 8 is a sectional view taken upon the line 8—8 of Fig. 7.

Fig. 9 is a view similar to Fig. 7 after the parts have been arranged in a desired relation showing the parts of the pattern partially assembled.

Fig. 10 is a fragmentary plan view of the same.

Fig. 11 is a view similar to Fig. 9 showing the parts of the pattern fully assembled.

Fig. 12 is a sectional view through one of the character bands carried by one of the rules forming part of the pattern.

Figs. 13, 14 and 15 are sectional detail views of the mechanism carried by each rule for spacing the rules in any desired series of groups.

Fig. 17 is a sectional view taken upon the line 17—17 of Fig. 16.

Figs. 18 and 19 are diagrammatic views illustrating the action of the mechanism for separating the rules a predetermined distance apart.

Fig. 20 is a fragmentary vertical sectional view partly in diagram showing the mechanism for controlling the movement of a pattern during assembly.

Fig. 21 is a fragmentary plan view of a portion of the mechanism shown in Fig. 20.

Fig. 22 is a detail view of the magnetic reversing switch shown in diagram in Fig. 20.

Fig. 23 is a detail view of the magnetic brake shown in diagram in Fig. 20.

Figs. 24, 25, 26 and 27 are fragmentary detail views of a portion of the mechanism shown in

Fig. 20 and illustrating different positions of the parts.

Figs. 28 and 29 are diagrammatic views illustrating successive steps of a part of the mechanism for separating the rules a predetermined distance apart.

Figs. 30, 31 and 32 are fragmentary vertical sections of a portion of the mechanism showing the matrices and the mold together with their associated parts in different positions.

Fig. 33 is a fragmentary plan view of a portion of the mechanism shown in Fig. 30.

Fig. 34 is a fragmentary front elevational view of a portion of the mechanism shown in Fig. 31, with the parts in different positions.

Fig. 35 is a sectional view taken upon the line 35-35 of Fig. 31.

Fig. 36 is a fragmentary front elevational view of a portion of the mechanism shown in Fig. 32, with the parts in different positions.

Fig. 37 is an enlarged vertical sectional view of the crucible and mold.

Figs. 38, 39 and 40 are sectional detail views of the mold showing the parts in different positions.

Fig. 41 is a perspective view of a cast line of type.

Figs. 42 and 43 are detail vertical sectional views of the mold and galley showing the parts in different positions.

Figs. 44 and 45 are plan views of the portions of the mechanisms shown in Figs. 42 and 43 respectively.

Fig. 46 is a fragmentary detail vertical sectional view of the mold.

Figs. 47 and 48 are similar sectional elevational views of a portion of the machine showing the parts in different relations.

Fig. 49 is a fragmentary detail view of the track construction for supporting the patterns.

Figs. 50 and 51 are sectional views showing a portion of the mechanism illustrated in Figs. 47 and 48 and with the parts in the same relations respectively.

Fig. 52 is a transverse sectional elevational view of a portion of the mechanism.

Fig. 53 is a detail elevational view of a portion of the machine.

The present invention and principles underlying it can be suitably illustrated by reference to the machine shown in the accompanying drawings for casting a line of type 520 (Fig. 41) in which the type groups are spaced to fill accurately and completely the entire predetermined space to be occupied by the line, in other words, a justified line. Such a machine comprises, in general, a single set of matrices 332 secured to arms 331 pivotally mounted in an arc shaped frame 328 similar to the type carrying arms of a typewriter. Each matrix is operatively connected to a separate operating bar 365 adapted to be moved indirectly by a character representation band 53 arranged to extend beyond the surface of one of the movable patterns P so as to swing the matrices into operative position to close the open top of a mold 323 containing metal or other impression receiving elements.

In the machine illustrated each pattern P contains a plurality of rules 24 each having a single group of character representation bands 53. These bands are adapted to be moved by mechanism actuated by the keyboard 103 to project beyond the surface of the pattern so as to actuate mechanism for moving the operating bars 365 to swing the matrices 332. The rules 24 also

contain differential and justification space means for spacing the character representation bands 53 a predetermined distance apart and in groups spaced apart so that as the pattern is moved to actuate the matrices justified groups of impressions are produced in the metal.

The specific construction of the machine will now be described.

The various parts are supported by a casing 100 having front and rear walls 97 and 98 respectively and side walls 101 and 102 enclosed by a top 99. Spaced pairs of vertical guideways 250 and 251 are suitably fixed upon the opposite sides of the casing.

A slide 252 extends between and engages the guideways 250 and is provided with an upwardly extending projection 253 intermediate its ends carrying a platform 254 which yieldably supports a plate 255. A vertically extending projection 256 is provided near each end of the slide 252 and each is provided near its upper end with an inwardly extending stud 257 adapted to receive one of the forked ends 258 of a lever 259 pivotally mounted upon a stud 260 fixed in the opposite side walls of the casing.

A slide 262 extends between and engages the pair of slideways 251. A platform 263 is fixed upon the slide 262 and carries two pair of upwardly extending posts 264 and 265. A plunger 266 is movably mounted in each of the posts 264 near their upper ends and each carries a track section 2 at one end. The other end of each of the plungers 266 is provided with an enlargement 267 adapted to be received in an enlarged opening 268 in the post 264. Each track section 2 is normally held retracted against the post by a spring 269 surrounding plunger 266 with one end engaging the enlargement 267 and its other end engaging the end of the opening 268. Pins 270 fixed in the casing extend inwardly therefrom into the path of movement of the track sections 2 thereby moving the track sections away from the posts 264 when the slide 262 is moved upwardly. An upwardly extending projection 272 is provided near each end of the slide 262 and each is provided with a stud 273 adapted to receive the other forked ends 274 of the levers 259. One of the studs 273 is extended outwardly through a slot 275 in one side of the casing to be received in a slot 276 provided intermediate the ends of a manually operable lever 277 one end of which is pivotally mounted in a bracket 278 carried by the rear wall of the casing. A plate 279 extends between and is suitably secured upon the upper ends of the posts 264. The upper rails 282 (see Figs. 1 and 49) are pivotally mounted upon brackets 283 fixed in the opposite side walls of the casing and each is provided with a lug 284 adapted to engage the bottom of the bracket 283 and serve as a stop for maintaining the track in its normal position for receiving a pattern. A spring 285 tends to hold the track in its normal position with the lug 284 in engagement with the bracket 283, but permits the track to be turned and pivoted upward.

A plurality of pairs of track sections 96 forming lower tracks are suitably secured within the casing in spaced relation so as to permit the track sections 2 to pass therebetween.

The patterns P are identical in construction (see particularly Figs. 1, 6, 7, 8, 12, 13, 14 and 15) and each comprises a hollow frame having longitudinal walls 20 and 21 connected by end walls 22 and 23. The end walls 22 and 23 are provided with depending projections 281 for a purpose described hereinafter. A pin 711 pro-

jects from the wall 21 of each pattern for a purpose described hereinafter. A plurality of rules 24 extend between the walls 20 and 21 and are held in the frame by flanges 25 extending inwardly from the edges of each of the walls 20 and 21. Projections 26 and 26' extend from one of the walls of each pattern for a purpose described hereinafter. A plurality of plungers 27 extend through the end wall 23 and are slidably mounted in bearings 28 therein. A backing plate 29 extending between walls 20 and 21 is fixed upon the inner ends of the plungers 27 and is retained within the frame by the inturned flanges 25. The backing plate 29 is forced in engagement with the rules 24 to urge them towards the end wall 22 by a spring 30 surrounding each of the plungers 27 and extending between the backing plate 29 and the end wall 23. Each of the walls 20 and 21 is provided with a longitudinal opening 30 for a purpose to be described hereinafter.

The legs 31 of a U-shaped bar 32 extend through a hollow cylinder 33, suitably secured near the rear end of each of the walls 20 and 21, and are adapted to slide in bearings 34 formed in the closed end 701 of the cylinder. A stop 35 is fixed upon each of the legs 31 and normally is held in engagement with the closed end 701 of the cylinder 33 by a spring 36 surrounding each leg and extending between the stop 35 and a cap 37 threaded in the other end of the cylinder. A cam block 38 is mounted upon the end of each of the legs 31 and is fixed in desired position thereon by a set screw 39. A shaft 40 is rotatably mounted in brackets 41 and 41' fixed upon the end wall 23. An arm 42 is fixed upon each end of the shaft 40 and carries a cam follower 43 at its free end adapted to engage the cam block 38. Arms 45 are fixed upon the shaft 40 one above each of the plungers 27 and are adapted to be moved into engagement with the plungers 27 by springs 47 one end of each of which is fixed to one of the arms 45 and the other ends of which are fixed to a pin 48 carried by the brackets 41'.

Each of the rules 24 comprises a strip of metal or the like provided with spaced transverse recesses 50 in one side face. The intermediate portion 51 between the recesses 50 is provided with a longitudinal slot 52 between the side faces of the rule in which a plurality of bands 53 are mounted for movement transversely thereof. Each of the bands 53 is provided near the top thereof with a character representation, such as a letter, number, punctuation mark or the like. One edge of each of the bands is provided with a recess 53a directly below the character representation. Parallel grooves 54, 55 and 56 are provided in one face of each band and are adapted to engage a wire 57 fixed in the rule and extending longitudinally through the slot 52. A justifying element 58 is suitably mounted in each of the recesses 50 and comprises a body 59 adapted to slidably support a space band 60. A pair of links 61 are pivotally connected at one end to a spreading member 62 the upper edge of which is adapted to slidably engage spaced lips 50' projecting from the next adjacent rule 24 into the recesses 50. The other end of each of the links 61 is shaped in the form of a cylinder 63 adapted to be received in a similarly shaped socket 64 in the body 59. Each cylinder 63 is provided with a slot 65 of gradually increasing depth. A roller 66 is positioned in each slot 65 and is held in engagement with the bottom thereof and with the socket 64 by a spring 67 extending between

the roller 66 and the end wall of the slot 65. The space band 60 is provided with cams 68 adapted to engage the rollers 66 and move them in the slot 65 against the action of the springs 67.

A shaft 70 is pivotally mounted in ears 71 extending from one face of each of the end portions 72 of each rule 24. A plate 73 is fixed upon each shaft 70 so as to swing toward or away from the face of the end portions 72. A shaft 74 is rotatably mounted in each plate 73 so as to extend across a recess 75 formed in one face thereof and above the pattern. A pair of pawls 76 are positioned in the recess 75 and are fixed in spaced relation upon the shaft 74 by pins 77. A spring 78 surrounding the shaft 74 with one end in engagement with one of the pawls 76 and its other end in engagement with a lug formed on the plate 73 normally holds the pawls 76 in position so that their free ends may engage spaced sets of teeth 79 formed upon the adjacent face of the end portions 72.

A bracket 81 extends outwardly from each of the walls 20 and 21 and carries a screw sector 82 at its free end. A plunger 83 is yieldably mounted in each of the brackets 81 and carries a screw sector 84 at its free end. The screw sectors 82 and 84 are adapted to engage screws for a purpose described hereinafter.

A pair of spaced parallel shafts 140 are mounted for rotation in bearings 141 fixed in the casing 105 and are provided with screw portions 140' adapted to engage the screw sectors 84 to move the upper pattern P along the upper track 282. Each of the shafts 140 is provided at one end with a bevel gear 142 adapted to engage a bevel gear 143 upon 110 a transverse shaft 144. The transverse shaft is provided with a worm wheel 145 adapted to engage a worm 146 upon the armature shaft of a motor M'. A pair of spaced parallel shafts 148 are rotatably mounted in bearings 149 carried by 115 the casing and are provided with screw portions 148' adapted to engage the screw sectors 82 to move the pattern P along the lower rails formed by the track sections 96. One end of each of the shafts 148 is provided with a bevel gear 150 adapted 120 to engage a bevel gear 151 upon a transverse shaft 152 carrying a worm wheel 153 adapted to engage a worm 154 upon the armature shaft of a motor M'.

The other end of one of the shafts 148 is provided with a bevel gear 155 (Fig. 20) adapted to engage a bevel gear 156 on a transverse shaft 157 rotatably mounted in bearings in the casing so as to position the shaft 157 adjacent an opening 159 in the front wall of the casing 100. An intermediate portion of the shaft 157 is formed with a screw 160 adapted to engage a screw sector 161 carried by a table 162 extending forwardly through the opening 159. An indicating pointer 200 is secured upon the table 162 so as to extend 135 adjacent a scale S upon the upper portion of the outer face of a guide bar 163 suitably secured to the front wall of the casing so as to extend upwardly in back of the opening 159. The inner or rear edge of the table 162 is provided 140 with a downwardly extending projection 164 adapted to be received in an L-shaped slot 165 in the guide bar 163. The screw sector 161 is normally held in engagement with the screw 160 by springs 166 extending between the table 162 and 145 the upper edge of the L-slot 165.

Suitable means is provided for controlling the movement of the pattern P so as to bring the rules 24 successively directly over vertically movable slides 111 slidably engaging guideways 150

- 94 so that any one of the character representation bands 53 on the rules can be engaged by the end of one of the slides 111. For this purpose each of the slides 111 is provided with one or 5 more teeth 170 adapted to engage a toothed cylinder 171 carried by a shaft 172 mounted for rotation in suitable bearings fixed to the casing. Some of the slides 111 are provided with a greater number of teeth 170 than others for the purpose 10 described hereinafter. A gear 173 is connected with the shaft 172 by an overrunning clutch 173' which constitutes a one-way driving connection. The gear 173 is adapted to engage a rack 174 formed as a part of a rod 175 15 which is slidably mounted in a sleeve 176 in which it is held by the resilient pressure of a spring 177. One end of the rod 175 extends through the front wall of the casing and is provided with a knob 178. The other end of the rod is adapted 20 to engage the rear wall of the casing to limit the rearward movement of the rack 174. The rack 174 carries a switch A having a pivoted arm 178 connected with a conductor 220 and a fixed contact 19 connected with conductor 219. 25 The arm 178 is arranged to be engaged by the projection 26 on the pattern P to open the switch A against the action of a spring 179. Each of the slides 111 is provided with a projection 180 adapted to engage the pivotally mounted arm 181 30 of a switch 203 suitably carried by the casing to move the same against the action of a spring 182 when the slide 111 is moved upward. The arm 181 is connected with conductor 218 and is adapted to move into and out of engagement 35 with a contact 18 fixed in the switch 203 and connected with the conductors 219 and 223.
- The keyboard 103 which is similar to an ordinary typewriter keyboard, is suitably supported adjacent the front wall 97 of the casing. It is 40 provided with two shift keys 104 carried by one end of bars 105 extending through an opening 96 in the wall 97 and pivotally mounted at an intermediate point upon a shaft 106 fixed in the casing. A bracket 107 is carried by the other 45 ends of the bars 105. A rod 108 is mounted in the bracket 107 for pivotally supporting a plurality of bars 109 each carrying a character key 110 at one end. The bars 109 normally abut the top edge of the opening 96 in the wall 97 of the casing. The other end of each of the bars 109 is 50 adapted to engage a notch 95 in one of the slides 111 previously referred to. Each of the slides 111 is normally maintained in the position shown in Fig. 1 by a spring 112 one end of which is fixed 55 to the slide and the other end of which is secured to the ways 94. The slides 111 are so arranged that there is one positioned below each of the character bands 53 in a rule 24 and they are 60 adapted to be moved upward to move the corresponding bands so that they project beyond the surface of the pattern.
- It should be noted here that a suitable number of teeth 170 are arranged on the slides 111 in such positions as to cause the rack 174 to move 65 forwardly an amount equal to the distance that the rules 24 are moved rearwardly by plates 73 forming part of the space differential mechanism as more fully described hereinafter. The space differential mechanism is provided for the 70 purpose of separating the corresponding faces of the character bands 53 carried by the rules during assembly of the pattern an amount proportional to the width of the character represented by the character bands 53. The characters 75 may be divided into a plurality of classes depend-
- ing upon the width of the character. In the present instance, the thickness of the rules is taken as being proportional to the width of the characters in the class of characters of minimum width. Therefore, when a character band 53 80 corresponding to a character of the minimum class is selected in a rule 24, as more fully described hereinafter, it is not necessary to move the remaining rules in the pattern rearwardly. However, when a character band 53 in a rule is selected which represents a character in any of the other classes, the remaining rules must be moved rearwardly an amount proportional to the width of the character. 85
- For this purpose, each of the bars 109 is provided with a projection 113, 114 or 115 extending upwardly from a point thereon between its pivot 108 and the rear end of the bar depending upon the class of characters which includes the character represented by the bar 109. If the character is in the class of characters having the maximum width, then the bar 109 is provided with the projection 113, which is located farther from the pivot 108 than the projections 114 or 115. The projections 114 and 115, which are on bars representing characters in the other two classes, are located thereon nearer the pivot 108. 90
- The projection 115 is positioned upon the bars 109 which correspond to the characters of minimum width so that when the character key carried by the bar is depressed to elevate a character band 53 in the pattern so as to represent a small letter, the upward movement of the projection 115 is insufficient to move links 123 so as to cause the wedges 126 to move between the plates 73 and 105 the pawls 76 as described hereinafter. However, when the shift key is depressed the rod 108 carrying the bars 109 is raised an amount such that when one of the keys carried by the bars 109 is depressed the projection 115 will move upwardly 110 to a point such as to cause the wedge to spread the plates 73 and pawls 76 to separate the corresponding faces of adjacent rules an amount proportioned to the width of the impression to be produced by a character of this class. The projections 114 carried by the bars 109 which correspond to the characters in the next class are positioned upon the bars 109 so that when the keys are depressed the projections 114 will move upward 115 to move the wedges 126 to spread the plates 73 and pawls 76 to separate the corresponding faces of adjacent rules an amount proportioned to the width of the impression to be produced by a character of this class. If the character band, elevated by one of the bars corresponding to 120 characters in this class, is to represent a capital letter then the shift key is depressed before the key carried by the bar 109 is depressed, thus causing the projection 114 to move upwardly to a higher point and consequently move the wedges 126 inwardly a greater distance so as to spread the plates 73 and pawls 76 a greater distance apart. Likewise, the projections 113 are positioned upon the bars 109, which correspond to characters of the next larger class, at a point farther from the rod 108 so that the projections 113 will rise to actuate the wedges 126 and spread the plates 73 and the pawls 76 to separate corresponding faces of the adjacent rules an amount proportional to the width of the impressions to be produced by the characters of this class. If it is desired to raise a character band 53 to represent a capital letter of this class then the shift key is actuated before the key carried by the bar 109 is depressed. The arrangement is such that when the shift key is 130 135 140 145 150

depressed before depressing the keys carried by the bars 109 corresponding to the characters of the first and second class, the differential mechanism is actuated to spread the plates 73 and 5 pawls 76 an amount equal to the distance the plates 73 and pawls 76 will spread when the character keys carried by the bars 109 corresponding to the third class of characters are depressed to elevate a character band 53 which is to represent 10 a small letter.

The keys marked "em", "en" and "thin" on the keyboard which actuate so-called blank matrices to close the mold for the purpose of casting a blank portion in the line of type or slug are provided 15 with mechanism similar to that above described for moving the wedges 126 if the blanks are of a width greater than that of the minimum class of characters. If however the width of any of the blanks is equal to that of the minimum class of 20 characters, no spacing of the remaining rules is required and therefore the bar 109 which elevates the band representing this blank in the pattern is not provided with a projection similar to the projection 113, 114 or 115 above described.

25 If desired, the projections 113, 114 and 115 may be adjustably mounted upon the bars 109 so that their distance from the rod 108 may be changed to change the point at which the projections 113, 114 and 115 will rise when the character keys carried by the bars are depressed so as to vary the 30 extent to which the differential mechanism is actuated. In such case, the matrices 332 would be detachably mounted in the bars 331 so that they could be replaced by other matrices having 35 characters of a different width.

The projections 113, 114 and 115 are adapted to engage transverse bars 116, 117 and 118 respectively. The ends of each of the bars 116, 117 and 118 are bent upwardly and rearwardly and are 40 pivotally mounted at spaced points in brackets 119 secured to the side walls of the casing. A rod 122 connects the rear end of each of the rods 116, 117 and 118 and is pivotally connected to the links 123 which extend upwardly outside of the lower 45 track. The upper end of each of the links 123 is connected to a toggle 124 one end of which is fixed in a bracket 125 on the casing and the other end of which is fixed upon a wedge 126 slidably mounted in the bracket 125 to move through the 50 openings 80 in the walls 20 and 21 of the pattern to spread the plate 73 and pawls 76 to bring the latter into engagement with one of the teeth 79 and to cause the plate 73 to engage the adjacent rule 24 and move the remaining rules rearwardly 55 an amount proportional to the width of the character corresponding to the character representation on the character band 53 above the slide 111.

A space bar is provided in the keyboard 103 and 60 extends between the forward ends of bars 130 pivotally mounted upon studs 131 in opposite side walls of the casing 100. A link 132 is pivotally connected to the rear end of each of the bars 130 and extends upwardly and is pivotally connected at its upper end to a toggle 133, one end of which is pivotally mounted in a bracket 134 fixed to the casing and the other end of which is pivotally connected to a pin 135 slidably mounted in a lug 136 secured to the underside of the lower 65 track so as to be moved into engagement with the spacing member 58 to move the same longitudinally along the rule 24 into a position to be operated by the plate 255. One of the bars 130 is provided near its rear end with an arm 16 adapted to engage a notch in a slide 17 slidably

mounted in the ways 94 and provided with teeth 15 adapted to engage the toothed drum 171.

The keyboard 103 is also provided with a reversing key 189 carried upon one end of a bar 190 pivotally mounted at an intermediate point upon a rod 191 carried by the casing. A spring 705 connected to the casing and the bar 190 normally holds said bar in engagement with the casing at the upper side of the opening 96. A link 192 is pivotally mounted at one end near the other end of the bar 190 and extends upwardly therefrom. The link 192 is provided with a forked upper end 193 adapted to engage a pin 600 carried by the switch arm 181 so as to open the switch when the reverse key is depressed. A slot 194 is provided at an intermediate point on the link 192 and is adapted to receive a pin 195 upon the end of a pivoted arm 196 carried by a switch 204 having a fixed contact 601 connected with a conductor 227. The arm 196 is connected with a conductor 228 and is adapted to move into and out of engagement with the contact 601. A spring 602 normally holds the arm 196 in engagement with the contact 601.

The motor M' which is preferably an alternating current motor of the three-phase type, is supplied with electrical energy by three feed lines L¹, L² and L³ (see particularly Fig. 20). This motor is controlled by a magnetic reversing switch R which comprises two triple pole magnetically operated contactors *a* and *b* which are wired as shown in Figs. 20 and 22 so that when contactor *a* is closed the motor operates in one direction and when the contactor *b* is closed the motor operates in the reverse direction. The contactors *a* and *b* are closed by operating coils 201 and 202 respectively which are controlled by separate circuits connected with the feed lines, both circuits being controlled by a manually operated two-switch control station D having the "forward" switch 203 and the "reverse" switch 204. A "stop" switch 205 is also provided to stop the motor at any desired time. Each circuit is further controlled by the limit switch A and a limit switch B which are operated automatically by 105 the movement of the pattern P, the limit switch A being opened by engagement of the pivoted arm 178 thereon with the projection 26 depending from the pattern. A switch B constructed the same as switch A is arranged to be opened 110 by the engagement of the pivoted arm carried thereby with a projection 603 depending from the pattern when the pattern is moved in a reverse direction.

The contactor *a* comprises fixed and movable members, the latter being pivotally mounted on the frame 206 of the reversing switch, and being provided with an armature 207 which cooperates with the coil 201 when the latter is energized 120 to close said contactor. An interlock *e*, operated by the contactor *a* and provided for the purpose of closing its operating circuit comprises a movable member 209, yieldingly mounted in the movable member of said contactor, and fixed members 210 secured to the frame 206. The contactor *b* comprises fixed and movable members, the latter being pivotally mounted on the frame 206 and being provided with an armature 211 which cooperates with the coil 202 when the latter is energized to close said contactor. An interlock 135 *f*, operated by the contactor *b* and provided for the purpose of closing its operating circuit comprises a movable member 212 yieldingly mounted in the movable member of said contactor and fixed members 213 secured to the frame 206. 140

145 150

These interlocks *e* and *f* are closed when both contactors are open to permit the use of either operating circuit to the exclusion of the other. The contactors *a* and *b* are also interlocked by a bar 214 pivoted intermediate its ends to the frame 206, said ends being secured by links 215 to each of the movable members of said contactors. This construction prevents both contactors being closed at the same time.

- 10 The circuit for controlling the reversing switch to operate the motor to move the pattern *P* in a forward direction is shown by light full lines in Fig. 20. Assuming the value of the current in line *L*¹ to be zero at a certain instant the current in lines *L*² and *L*³ will be of equal value but of opposite polarity. With the "forward" switch 203, the "stop" switch 205 and the limit switch *A* all closed, the current coming in through the line *L*² will flow through wire 216, operating coil 201, wire 217, interlock *e*, wire 218, "forward" switch 203, wire 219, limit switch *A*, wire 220, "stop" switch 205, wires 221 and 222, and out through line *L*³. When the current in line *L*¹ is positive and the currents in lines *L*² and *L*³ are negative, the flow will be through the line *L*¹ and wire 223 to one side of the "forward" switch 203 where part of it will pass through said switch and thence through wire 218, interlock *e*, wire 217, coil 201, wire 216 and out through line *L*² and the remainder will pass through wire 219, limit switch *A*, wire 220, "stop" switch 205, wires 221 and 222 and out through line *L*³. A switch 240 mounted on the front wall of the casing connects the conductors 219 and 220.
- 35 The passage of the current thus described causes the operating coil 201 to be energized and the contactor *a* to be closed, which connects the feed lines *L*¹, *L*² and *L*³ with the motor *M*¹ to drive the latter in a direction to move the pattern *P* forwardly. The circuit just described keeps the operating coil 201 energized when the aforesaid switches are closed regardless of the polarity of the feed lines and thus insures a forward movement of the pattern *P* until the limit switch *A* is automatically opened or the "stop" switch 205 is manually opened in case of an emergency.

The circuit for controlling the reversing switch to operate the motor *M*¹ to move the pattern *P* in a reverse or rearward direction is indicated in light dot and dash lines in Fig. 20. With the limit switch *B* closed, the current may flow, according to the polarity of the feed lines, through line *L*³, wires 216 and 225, operating coil 202, wire 226, interlock *f*, wire 227 "reverse" switch 204, wire 228, limit switch *B*, wire 229, "stop" switch 205 and back to the line *L*³ through wires 221 and 222 which are common to both circuits. Or the current may flow through the line *L*¹, wires 230 and 231 to one contact of the interlock *f*, where part of the current will flow through wire 227, "reverse" switch 204, wire 228, limit switch *B*, wire 229, "stop" switch 205 and the wires 221 and 222 to the line *L*³, while the remainder flows through interlock *f*, wire 226, coil 202, and wires 225 and 216 to line *L*².

The operating coil 202 thus energized closes the contactor *b* which connects the feed lines with the motor to throw the latter "across the line" and thus reverse its rotative direction. These circuits keep the operating coil 202 energized when the aforesaid switches are closed regardless of the polarity of the feed lines and thus insure movement of the pattern *P* in a reverse or

rearward direction until stopped automatically by the opening of the limit switch *B*.

A magnetic brake 241 is provided for the armature shaft of the motor *M*. This brake (see Figs. 20 and 22) comprises a drum 242 secured to said shaft and adapted to cooperate with shoes 243 and 244 carried by arms 245 and 246 pivoted at 247 to a fixed portion of the mechanism. Springs 248 tend to hold the shoes normally in engagement with the drum. The upper ends of said arms are pivotally connected as shown to one end of a lever 249 which is itself pivotally connected to the core 9 of a solenoid *W*, which is connected by wires 231 and 232 with the feed lines. When the solenoid is energized the lever 249 is actuated to move the shoes out of engagement with the drum in opposition to the springs 248.

A second pair of vertical guideways 290 are positioned upon opposite side walls of the casing adjacent the pair of guideways 251 and are adapted to receive a slide 291 which extends therebetween. A pair of plates 292 are each pivotally mounted at one end upon a rod 293 carried by the slide 291 and are normally held in engagement with the stops 294 by a spring 295 connecting the arms. A lever 296 is pivotally mounted at an intermediate point upon a rod 297 suitably fixed in the casing and is pivotally connected at one end to the slide 291. One end of a link 298 is pivotally connected to the other end of the lever 296 and its other end is pivotally connected to the end of the reversing rod 190. A rod 300 is slidably mounted in a bearing 301 fixed in the casing and is engaged at its lower end by the reversing bar 190 between the pivot 191 and the key 189. The upper end of the rod 300 is provided with an inclined plate 302 serving as a cam when the key 189 is depressed to engage the projected bands 53, and 60, and the shafts 74 to 115 return the same to their initial positions.

A bracket 320 (Fig. 1) is suitably fixed upon the rear wall of the casing and extends rearwardly therefrom. A post 321 is suitably mounted upon the bracket 320 and carries a table 322 for movably supporting the mold 323 having an open top 324 as more fully described hereinafter. A bracket 325 is suitably fixed upon the rear wall of the casing above the bracket 320. The arc-shaped frame 326 is provided with guides 327 adapted to be received in guideways 328 suitably fixed upon the bracket 325. Ears 329 project from the ends of the frame 326 for supporting an arc-shaped rod 330 in spaced relation to the rear edge of the frame 326. A plurality of bars 331 are pivotally mounted upon the rod 330 and each carries at its free end a matrix 332 having characters *C* and *c* thereon.

The shaft 144 is provided with a sprocket 335 which is connected with a sprocket 336 upon a shaft 337 by a chain 334. A roll 340 is rotatably mounted in suitable bearings in the casing and is provided with a sprocket 339 which is connected with a sprocket 338 upon the shaft 337 by a chain 341. A roll 342 is rotatably mounted adjacent the roll 340 in suitable bearings in the casing and is provided with a sprocket 343 which is connected with a sprocket 344 on a shaft 345 rotatably mounted in suitable bearings 333 in the casing by a chain 332. A bevelled gear 346 is adapted to engage a bevelled gear 347 upon a shaft 348 rotatably mounted in bearings 349 supported upon the bracket 320. The shaft 348 is also provided with a bevelled gear 350 adapted to engage a bevelled gear 351.

on a shaft 352 rotatably mounted in suitable bearings carried by the bracket 320 and provided with a forward and reverse screw 353. The mold 323 is provided with an arm 355 carrying a lug 356 adapted to engage the grooves in the screw 353.

A slide 360 (Figs. 1 and 4) is slidably mounted in suitable guideways 331 on opposite side walls of the casing and is provided with suitable bearings for rotatably supporting a pair of spaced rolls 362. Springs 363 carried in the guideways 361 normally act upon the slide 360 to hold the rolls 362 in engagement with the rolls 340 and 342, thereby completing the driving connection 15 between the motor M² and the screw 353.

A plurality of levers 365 (Figs. 1 and 32) are pivotally mounted upon a rod 366 extending between the side walls of the casing and each extends between the slide 360 and the rolls 340 and 342. One end of each of the levers 365 is connected with one of the character bars 331 by a link 367. A plurality of trip fingers 368 are pivotally mounted upon a rod 369 extending between the side walls of the casing so that the upper end 25 of each normally supports the other end of one of the levers 365. Each lever 365 is held normally against one of the fingers 368 by a spring 700. A cam 370 is rotatably mounted in each of the levers 365 and is adapted to engage a roll 371 when the 30 fingers 368 are moved out of engagement with the levers 365. The cam 370 is provided with a pin 318 adapted to engage a stop 319 fixed in the casing. The roll 371 is provided with a sprocket 3 which is connected with a sprocket 373 on the 35 shaft 337 by a chain 374. A lever 375 is also pivotally mounted upon the rod 366 so as to extend between the slide 360 and the rolls 340 and 342. A trip finger 376 is pivotally mounted upon the rod 369 and normally supports one end of the 40 lever 375 so as to depress the slide 360 to maintain the rolls 362 out of engagement with the rolls 340 and 342.

A lever 380 is pivotally mounted at an intermediate point in a bracket 381 carried by the 45 casing. The forked end 382 of the lever 380 is adapted to engage a pin 383 fixed upon a rod 384 extending into a crucible 385 more fully described hereinafter. A cam 387 is rotatably mounted in the lever 380 near its other end and is adapted to 50 engage a roll 388 rotatably mounted in suitable bearings carried by a bracket 389 fixed upon the top of the casing. The cam 387 normally is maintained in engagement with the roll 388 by a spring 390. The roll 388 is provided with a sprocket 391 which is connected with a sprocket 392 upon the 55 roll 340 by a chain 393. The cam 387 is provided with a pin 394 adapted to engage a stop 395 carried by a bracket 396 fixed upon the top of the casing. An arm 397 is suitably fixed upon the 60 slide 360 so as to extend upwardly therefrom beneath the lever 380 so as to move the forward end of the latter upwardly when the rolls 362 are in engagement with the rolls 340 and 342.

An arm 400 is pivotally mounted at one end 65 upon a plate 401 carried by the bracket 320 and is normally held against a stop 402 upon the plate 401 by a spring 403. Means are provided for moving the arm 400 to bring its free end in engagement with the matrices 332 to hold the 70 latter in engagement with the open top 324 of the mold 323. For this purpose one end of a core 404 of a solenoid 405 is pivotally mounted upon a pin 406 upon the arm 400. The ends of a pair of bars 408 (Fig. 31) are resiliently mounted in spaced 75 insulated boxes 409 carried by the casing 100 and

provide electrical contacts adapted to be engaged by the levers 365 which may be of metal or provided with a metal insert adapted to bridge the contacts 408. The conductors 410 leading from the solenoid 405 are connected to a battery 411 or other suitable source of electrical energy and are also connected with the contacts 408.

A rod 415 is slidably mounted in a cylinder 416 closed at one end. A nut 417 is fixed upon the rod 415 and is adapted to engage the closed end 418 of the cylinder and is normally held thereagainst by a spring 435 surrounding the rod 415 with one end in engagement with the nut 417 and its other end in engagement with a plug 419 threaded in the open end of the cylinder. One end of the rod 415 is provided with a pin 420 adapted to be received in an elongated slot 421 formed in one end of a lever 422 pivotally mounted at an intermediate point upon a bracket 423 carried by the casing. The forked end 424 of the lever 422 is adapted to engage a pin 425 carried by a lug 426 depending from the arc-shaped frame 326. A bar 430 extends laterally from the other end of the rod 415 and is provided with a plurality of forwardly projecting fingers 431 adapted to be engaged by one 90 of the levers 432 pivotally mounted upon the rod 369 adjacent each of the trip fingers 368. Each of the levers 432 is provided with a pin adapted to engage the adjacent finger 368.

The mold 323 comprises a side wall 440 provided at its lower edge with an L-shaped projection 441 adapted to be received in an L-shaped guide slot 442 formed in a projection 443 extending upwardly from the front edge of the platform 322. One end of the mold is closed by a wall 445 extending from one end of the wall 440. A groove 447 is provided in the wall 445 and extends along the inner face thereof. A member 448 is suitably secured to the side wall 440 near its other end and extends from near the lower edge thereof and is provided with a groove 449. The mold bottom 450 extends between and is slidably mounted in the grooves 447 and 449 and is provided with a pair of upwardly extending pins 7. A projection 452 extends upwardly from the member 448 parallel to the side wall 440 and spaced therefrom a distance substantially equal to the width of the mold. A rod 453 extends between the projection 452 and the end wall 445 and is suitably mounted near the top thereof. A side 125 wall 455 is pivotally mounted upon the rod 453 and is provided near its lower edge with a pair of outwardly extending lugs 8 each having an elongated slot 9 adapted to receive one of the pins 7 in the mold bottom 450. The top edge of 130 each of the side walls 440 and 455 of the mold is provided with an inwardly extending lip 477 against which the matrices 332 rest when moved into operative engagement with the open top of the mold. A leaf spring 458 is suitably secured 135 at an intermediate point to the side wall 455 and is curved outwardly so that its ends engage a bracket 460 suitably secured upon the platform 322. Springs 461 are each secured at one end to the side wall 455 near the bottom edge thereof and at the other end to a pin mounted near the outer edge of the mold bottom 450. A roll 465 is suitably mounted in the mold bottom 450 so as to depend from the lower face thereof and is adapted, when the mold is moved to one end of its path, to engage a cam 466 suitably secured upon the top surface of the platform 322.

The other end wall 467 is fixed upon the end of a discharge spout 468 which extends from the reservoir 385 into the mold between the side wall 135

440 and the projection 452. The end wall 467 is provided with an opening 469 which connects the interior of the mold with the passage in the discharge spout 468. The other end of the discharge spout 468 communicates with a cylinder 470 within the reservoir 385 and is provided with a passage 471 providing a communication between the interior of the cylinder and the interior of the reservoir. A piston 472 fixed upon the lower end of the rod 384 is movable within the cylinder 470 to force molten metal from the cylinder through the discharge spout into the mold. The molten metal is maintained in fluid condition as it passes through the discharge spout 468 by an electrical coil 473 surrounding the spout and connected with a suitable source of electrical energy (not shown) by conductors 476. The metal in the crucible 385 is maintained in molten condition by an electrical heating element 474 supplied with suitable electrical energy from any suitable source (not shown) by conductors 475.

A U-bar 505 is provided at an intermediate point with an elongated slot 506 adapted to receive a pin 507 fixed in the casing. The rear end of the bar 505 normally engages a cam 508 projecting from the side wall 440 of the mold. The other end of the bar 505 is provided with a pin 509 adapted to be received in an inclined slot 510 near the lower end of the trip finger 376. A spring 511 is connected at one end to a pin 512 on the bar 505 between the slot 506 and the pin 509. The other end of the spring 511 is connected to a pin 514 secured to the rear wall of the casing.

Referring to Fig. 41 there is shown a cast line of type or slug made by successive operations of the plunger 472 in a crucible containing molten type metal. The individual casts which are defined by the broken lines indicated at d are fused during the casting operation to produce an integral slug similar to that formerly produced by a single operation.

A galley 480 is suitably secured upon the bracket 320 below the opening 481 in the platform 322. The bottom of the galley is provided with a longitudinal slot 482, the opposite edges of which are provided with a groove 483 adapted to receive guides (not shown) carried by a slide 484 provided at one end with an upwardly extending arm 485 for retaining the cast slugs 610 thereon. A rack 486 is formed on the lower face of the slide 484 and is adapted to engage a pinion 487 fixed upon a shaft 488 mounted for rotation in suitable bearings 489 depending from the bottom of the galley. A ratchet 490 is suitably fixed upon the shaft 488 so as to engage a pawl 492 pivotally mounted upon one end of one arm 493 of a T-shaped bracket. The other arm 494 of the bracket is slidably mounted in guide ways 495 formed on one of the side walls of the galley 480. A roll 497 is carried by the other end of the arm 493 and is adapted to be engaged by a cam 498 depending from the side wall 440 of the mold. The pawl 492 is provided with a handle 500 which extends laterally therefrom under the galley 480 to a point adjacent a knurled wheel 501 upon the shaft 488 so that it may be conveniently gripped by the operator to move the pawl 492 out of engagement with the ratchet 490.

The operation of the machine is as follows: Before the machine is started in operation the pattern P is in the position shown in Figs. 1 and 20 with the limit switch A open and the front rule 24 directly over the slides 111. Electrical energy is supplied to the motor M² by closing a

switch (not shown) to rotate the screws 140. The switch 205 is then closed and the operator begins to assemble the character bands 53 in the rules 24 in a relation in the pattern corresponding to the relation of the impressions to be produced in the cast line of type. To accomplish this the operator depresses one of the keys 110 which corresponds to the character to be produced. This causes the corresponding slide 111 to rise to first cause the projection 180 thereon to engage the switch arm 181 to open the switch 203, and then to move the corresponding character band 53 above the surface of the pattern. As the slide 111 rises the teeth 170 thereon engage the drum 171 to rotate the same and cause the rack 174 to move to the left as viewed in Figs. 1 and 20 an amount proportional to the width of the corresponding impression to be produced. As the key 110 is depressed the wedges 126 (Figs. 18 and 19) are moved inward to swing the plates 73 to move the remaining rules rearwardly an amount equal to the distance the rack 174 moves, the plates being locked in these positions by the pawls 76. When the rack 174 is moved the arm 178 swings to close the switch A. The parts are now in the positions shown in Fig. 24. When the character key 110 is released the slide 111 is moved downwardly to its original position by the spring 112 and in so doing releases the arm 181 to permit the spring 182 to close the switch 203. The circuit through the motor M¹ is thus completed to cause the screws 148' to rotate and move the pattern P to bring the projection 26 again into engagement with the arm 178 to open the switch A and stop the motor M¹. The next rule 24 is now directly over the slides 111 as shown in Fig. 25. The character keys 110 are successively depressed until a character band 53 in each rule of a series of adjacent rules is raised to form a group to correspond with the first group of impressions to be produced, this group of impressions representing the first word of the line. The space bar is then depressed to move the links 132 upwardly to move the plungers 135 inwardly to engage the spacing elements 58 in the rule 24 adjacent to the last rule in which a character band has been raised and move the same transversely in the recesses 50 to a position to be actuated as described hereinafter. The depression of the space bar also causes the slide 17 to be raised to move the rack a distance equal to the thickness of a rule and permit the arm 178 to close the switch A. When the space bar is released the spring 182 moves the arm 181 to close the switch 203 thereby causing the motor M¹ to move the pattern P a distance equal to the thickness of a rule.

The character bands 53 of the succeeding rules 24 are then assembled in a similar manner in groups corresponding to the remaining groups of impressions in the line of type to be cast. The spacing members 58 carried by a rule 24 between each group of rules in each of which a character band has been raised, are selected as previously described in connection with the assembly of the first group. During assembly the rotation of one of the shafts 148 which carry the screws 148' causes rotation of the shaft 157 to move the screw 160 carried thereby and cause the indicator 200 to move along the scale S thus indicating to the operator when he has assembled all the complete groups in the pattern which can cause corresponding impressions in a cast line of type of a predetermined length. At this time the pattern is at rest with the limit switch 150

A open. The operator then moves the rack rearwardly until its rear end engages the rear wall of the casing. This not only closes the switch A but returns it to its initial position for beginning assembly. This causes the pattern to be moved forward until it rides off the screws 148' in the path of movement of the platform 254 and plate 255.

The operator then moves the lever 277 downward as viewed in Fig. 1 to cause the slide 252 to rise to bring the plate 255 into engagement with space bands 60 carried by the spacing elements 58 which have previously been selected during assembly. Further upward movement of the slide 252 causes the plate 255 to move the space bands 60 upwardly until the plate 255 engages the bottom of the space elements 58 whereupon the latter are moved upwardly to cause the links 61 to separate the member 62 therefrom. This causes all the assembled groups in the pattern, except the first, to be moved rearwardly together with the remaining rules in which the character bands have not been assembled until the last character band 53 engages the bar 32, whereupon the bar 32 is moved rearwardly to move the cams 38 out of engagement with the rolls 43 to permit the arms 45 to be moved into engagement with plungers 27 by the springs 47. This provides a resistance effective to stop the rearward movement of the rules so that the groups of assembled rules will accurately extend over a predetermined space in the pattern proportional to the length of the line of type to be produced. Due to the resistance thus encountered to the rearward movement of the rules 24 in the pattern P, further upward movement of the platform 254 causes the spacing elements 58 to act as stops preventing further upward movement of the plate 255 until the upward movement of the platform 254 has compressed the springs therebetween an amount sufficient to permit the platform 254 to engage the projections 261 depending from the pattern P. Further upward movement of the platform 254 raises the pattern P until it engages the tracks 282 to cause them to swing upwardly to permit the pattern to move above the same whereupon the springs 285 return the tracks 282 to their normal position. As the pattern is raised the screw sectors 84 are brought into engagement with the screws 140'. The lever 277 is then raised to return the slide 252 to its initial position during which the pattern P is lowered until it rests upon the rails 282. The rotation of the screws 140' causes the pattern to move rearwardly along the rails 282.

The rearward movement of the pattern P continues until the stop 711 upon the pattern engages the lower end of the trip finger 376 to move the latter to permit the springs 363 to move the slide 360 upwardly to bring the rolls 362 into engagement with the rolls 340 and 342 to complete the driving connection from the motor M² and rotate the screw 353 to move the mold 323. Further rearward movement of the pattern causes the raised character band 53 in the rule nearest thereto to engage the trip finger 368 corresponding thereto to move the finger from under the corresponding lever 365 thus permitting the spring 700 to turn the lever 365 counter clockwise as viewed in Figs. 30, 31 and 32. This permits the cam 370 to engage the constantly turning roll 371 to be rotated thereby to cause the lever 365 to turn in a clockwise direction and move the slide 360 downward to bring

the rolls 362 out of engagement with the rolls 340 and 342 thereby disconnecting the driving connection to the mold 323 to stop the same. In this manner the mold is moved a distance so as to separate the end walls 467 and 445 an amount equivalent to the width of the matrix 332. As the lever 365 is moved further through its clockwise path the link 367 swings the bar 331 to bring the lower character on the corresponding matrix 332 into engagement with the face of the mold to close the cavity just formed. Thereafter, the bar 365 then engages the contacts 408 to close the circuit through the solenoid 405 to cause the arm 400 to swing into engagement with the top of the matrix and hold the same in engagement with the mold. During the movement of the bar 365 the post 397 is moved out of engagement with the lever 380 to permit the cam to engage the continuously moving roll 391 and be rotated thereby to move the lever 380 in a clockwise direction and move the plunger 472 downwardly in the cylinder 470 to force molten metal through the spout 368 into the mold. As the pattern continues to move rearwardly the character bands 53 successively engage the trip fingers 68 corresponding thereto to successively actuate the mechanism above described.

It will be understood that the space bands 60 which project upwardly beyond the surface of the pattern between the groups of projecting character bands at one side of the pattern actuate a trip finger 368 to move a blank matrix into engagement with the face of the mold to produce a blank portion between the groups of impressions being cast. If the character represented by the character band 53 is a capital letter the band 53 projects upwardly beyond the surface of the pattern a greater distance than if it is representing a small letter. The position of the band 53 when corresponding to a small or capital letter is indicated in Figs. 34 and 36 respectively. The band 53 in the position indicated in Fig. 36 is such that as the pattern is moved rearwardly the recess 53a permits the character band to move past the corresponding trip finger 368 and engage the lever 432 corresponding to the band to move the lever in engagement with one of the fingers 431 and cause the rod 415 to move rearwardly to swing the lever 422 and move the frame 326 forwardly a distance sufficient to bring the character carried at the top of the matrix into engagement with the face of the mold when the matrix is moved into engagement therewith. As the lever 432 is moved by the character band 53, the pin 433 engages the trip finger 368 to swing the latter out of engagement with the corresponding lever 365 to cause the latter to move and actuate the mechanisms previously described.

After the last impression has been cast the mold 323 continues to move towards the galley 480 until the slug 610 is directly over the opening 481 in the platform 322. During this movement the cam 498 engages the roll 497 to move the slide 494 and cause the pawl 492 to actuate the ratchet 490 and move the slide 484 to feed the previously cast slugs 610 from the position shown in Fig. 42 to that shown in Fig. 43. Also, during the movement of the mold towards the galley, the roll 465 engages the cam 466 to withdraw the mold bottom 450 and swing the side wall 455 of the mold outwardly. As the side wall 455 is thus moved, the lip 477 thereon engages the top of the slug within the mold and ejects it through the opening 481.

as illustrated in Figs. 46 and 43. The mold then moves back from the galley during which movement the parts of the mold are restored to their normal positions. While the mold is returning to its starting position, the cam 508 (Fig. 33) engages the rod 505 to move it to swing the trip finger 376 to its normal position beneath the lever 375 as shown in Fig. 30. This causes the latter to turn in a clockwise direction to move the slide 360

10 downward and cause the rolls 362 to move out of engagement with the rolls 340 and 342 and stop the movement of the mold in its initial position.

The pattern continues to move along the upper tracks 282 until the screw sectors 84 have run off 15 the screws 140'. The pattern will then be positioned upon the track sections 265 which are supported upon the platform 263 carried by the slide 262. In the meantime, the operator has assembled another pattern and it has moved along the 20 lower rails 96 to a position above the platform 254 carried by the slide 252. The operator then moves the lever 277 downwardly as viewed in Fig. 1 causing the slide 252 to move upward and the slide 262 to move downward. The upward movement of the slide 252 causes justification of the 25 assembled groups in the pattern and elevation of the pattern to the upper tracks as previously described.

The downward movement of the slide 262 de- 30 posits the pattern upon the lower rails 96. During this downward movement, the plates 292 engage the inwardly positioned spacing elements 58 to move them outward to their initial positions in the recesses 50 in the rules. Further down- 35 ward movement of the slide 262 causes the plate 279 to engage the projecting character bands 53, space bands 60 and rods 74 to move the same downwardly. During the downward movement of the bands 60, the cams 68 thereon move the 40 rolls 66 to permit the spacing mechanism to collapse and the rules to move forwardly in the pattern to their initial positions under the action of the springs 30. The downward movement of the rods 74 carries the pawls 76 out of engagement 45 with the teeth thereby permitting the plates 73 to swing back to their normal positions. As the slide 262 moves downwardly after the pattern has been deposited on the lower rails, the springs 269 return the track sections 2 to the positions shown in 50 Fig. 51. The operator then moves the lever 277 upwardly to the position shown in Fig. 1, thereby causing the slides 252 and 262 to return to their initial positions. As the slide 262 returns to its initial position, the track sections 2 are engaged 55 by the pins 278 to return them to their initial positions forming part of the upper track as shown in Figs. 1 and 50. When the pattern P has been returned to the lower tracks, the screw sectors 82 are brought into engagement with the lower 60 screws 148 which at this time are rotating thereby causing the pattern to be advanced until the projection 26 engages the switch arm 178 and opens the limit switch A thus positioning the first rule 24 in the pattern directly above the slides 111 for the assembly of another line.

If, during assembly of the pattern, the operator makes a mistake such as depressing the wrong character key 110 or by starting to assemble a group of character bands which could not form an impression in the predetermined space occupied 70 by the cast line of type, he depresses the reverse key 189 which causes the link 298 to move the plates 292 out of the path of movement of the space elements 58. At the same time the link 192 75 is moved upwardly to open the switch 203. Fur-

ther upward movement of the link 192 permits the switch 204 to be closed. As the reverse key 189 is depressed the rod 300 is moved downwardly to bring the cam 302 into a position above the pattern to engage the projecting character bands 53, space bands 60 and rods 74. As the reverse switch 204 is closed the motor M' is actuated to rotate the screws 148' and cause the pattern to move rearwardly until the projection 26' (Fig. 20) thereon engages the switch arm to open the switch B to stop the motor M'. As the pattern moves rearwardly, the cam 302 engages the projecting character bands 53, space bands 60 and rods 74 to distribute the same in the manner previously described. When the reverse key is released the switch 204 is opened and the switch 203 permitted to close. At the same time the link 298 is moved downward by the action of the spring 705 to cause the plates 292 to move the spacing elements 58 outwardly to their initial positions in the rules. The operator then moves the rack rearwardly until its rear end engages the rear wall of the casing. This returns it to its initial position for beginning assembly. The pattern is now in position to be moved forwardly by the screws 148' until the projection 26 engages the switch arm 178 to open the switch A and stop the pattern in position for beginning the assembly there- 100 of.

The invention makes possible the provision of 105 a line-of-type casting machine of simple construction, the operation of which requires no special training and which is practically identical to the operation of an ordinary typewriter. In the machine of the invention a single set of matrices is utilized, yet the machine is capable of continuous operation due to the circulation of the patterns, one travelling through the phase of casting or forming impressions upon the impression receiving element, while the other is passing 110 through the phase of distribution, assembly and justification. The functions of assembling, justification and distribution are performed independently of the matrices which makes possible the use of a single set of matrices and continuous 115 operation. The machine has no parts which are disengaged or independent, as are the matrices and space bands in line casting machines heretofore commonly in use. On the other hand all the parts are secured in place and are limited as to 120 their movements. This has not been possible in previously existing machines which were capable of producing a justified line. The construction of the machine is such that if a mistake is made in assembling a line, the completely or partially 125 assembled line can be conveniently and readily cancelled before being cast.

The term matrix as used throughout this specification and in the appended claims is intended to include not only the character carrying members 130 of a line casting machine, but also any character carrying member adapted to produce an impression upon any suitable impression receiving element such, for example, as the type of a typewriter.

I claim:

1. In a machine of the type described, a single group of matrices having characters, means carrying an element for receiving impressions of certain of said characters, a pattern having character representations, means for spacing said character representations in said pattern so that their relationship to one another is similar to that of the impressions to be produced, and means for causing said character representations to ac- 145 150

- tuate said certain characters to produce said impressions.
2. In a machine of the type described a single group of matrices having characters, means carrying an element for receiving a series of groups of impressions of certain of said characters, a pattern having character representations, means for arranging said character representations in justified groups in each of which the character representations are spaced so that their relationship is similar to that of the impressions in the groups of impressions to be produced, and means for causing said character representations to actuate said certain characters to produce justified groups of impressions.
3. In a machine of the type described, a single group of matrices having characters, means carrying an element for receiving a series of groups of impressions of certain of said characters, a pattern having character representations, means for arranging said character representations in groups similar to the groups of impressions to be produced, means for adjusting the groups of character representations so they occupy a space representative of the space to be occupied by the groups of impressions to be produced, and means for causing said character representations to actuate said certain characters to produce said impressions.
4. In a machine of the character described, a single group of matrices having characters, means carrying an element for receiving a series of groups of impressions of certain of said characters, a pattern having character representations, means for arranging said character representations in said pattern similar to the impressions to be produced, said last means causing said character representations to be spaced so that their relationship is similar to that of said impressions, means for causing said arranged character representations to actuate said characters to produce said impressions, and means for restoring said character representations to their initial positions.
5. In a machine of the type described, a pattern comprising a plurality of series of character representations, means for arranging certain of the character representations in the pattern in a plurality of groups in each of which the character representations are arranged in a predetermined relation to one another, and means for adjusting the selected groups in said pattern so they occupy a predetermined space.
6. In a machine of the character described, a single group of matrices having characters, means carrying an element adapted to receive a series of groups of impressions of certain of said characters, a pattern having representations of said characters, means for moving said pattern through a predetermined path, a member operatively connected with each of said characters and adapted to be actuated to move said characters to produce said impressions, means operative as said pattern is moved through a portion of said path for arranging certain of the character representations in the pattern in groups similar to said groups of impressions to be produced, for spacing said groups of character representations an amount proportional to the spacing of said desired groups of impressions whereby said arranged character representations engage said members to move said certain characters to produce said desired impressions when said pattern is moved through another portion of said path, and means for restoring said character representations to their initial position after said members have been actuated.
7. In a machine of the character described, a single group of matrices having characters, a mold having two fixed dimensions, means for flowing metal into said mold to receive impressions of certain of said characters, a pattern having character representations, means for arranging the character representations in a desired relation on said pattern and spaced apart in the direction of travel of the pattern an amount proportional to the spacing of the impressions to be produced by said certain characters, means for moving said pattern to cause said arranged character representations to actuate said characters.
8. In a machine of the character described, a single group of matrices having characters, means carrying an element adapted to receive a series of groups of impressions of certain of said characters, a pattern having representations of said characters, means for moving said pattern through a predetermined path, a member operatively connected with each of said characters and adapted to be actuated to move said characters to produce said impressions, means operative as said pattern is moved through a portion of said path for arranging certain of the character representations in the pattern in groups similar to said groups of impressions to be produced, means for spacing the character representations in said groups so that their relationship to one another is similar to that of said impressions, means for spacing said groups of character representations an amount proportional to the spacing of said desired groups of impressions whereby said arranged character representations engage said members to move said certain characters to produce said desired impressions when said pattern is moved through another portion of said path.
9. In a machine of the character described, a single group of matrices having characters, means carrying an element adapted to receive a series of groups of impressions of certain of said characters, a pattern having representations of said characters, means for moving said pattern through a predetermined path, a member operatively connected with each of said characters and adapted to be actuated to move said characters to produce said impressions, means operative as said pattern is moved through a portion of said path for arranging certain of the character representations in the pattern in groups similar to said groups of impressions to be produced, means for spacing said groups of character representations an amount proportional to the spacing of said desired groups of impressions whereby said arranged character representations engage said members to move said certain characters to produce said desired impressions when said pattern is moved through another portion of said path, and means for restoring said character representations to their initial position after said members have been actuated.
10. A machine of the character described, a single group of matrices having characters, a mold having two fixed dimensions, means for flowing metal into said mold to receive impressions of certain of said characters, a pattern having character representations, means for arranging the character representations in a desired relation on said pattern and spaced apart in the direction of travel of the pattern an amount proportional to the spacing of the impressions to be produced by said certain characters, means for moving said pattern to cause said arranged character representations to actuate said characters.

- consecutively to produce said impressions, and means for varying the other dimension of the mold consecutively as each of said certain characters is actuated an amount corresponding to 5 the width of said certain characters respectively.
11. In a machine of the character described, a pattern comprising a plurality of rules, each rule including a single group of character representations, and means for spacing a plurality of groups 10 of rules to extend over a predetermined space.
12. In a machine of the character described, a pattern comprising a plurality of rules, each rule including a single group of character representations, means for spacing the rules a predetermined 15 distance apart, and means for spacing a plurality of groups of rules to extend over a predetermined space.
13. In a machine of the character described, a pattern comprising a plurality of rules, each rule including a single group of character representations 20 separately movable to project a predetermined distance beyond the surface of the pattern, and means for spacing a plurality of groups of rules to extend over a predetermined space.
14. In a machine of the character described, a pattern comprising a plurality of rules, each rule including a single group of character representations separately movable to project a predetermined 25 distance beyond the surface of the pattern, means for spacing a plurality of groups of rules to extend over a predetermined space, and means for holding the character representations in their projected positions.
15. In a machine of the character described, a pattern comprising a plurality of rules, each rule including a single group of character representations, means for moving a plurality of groups 30 of rules relatively, and means for limiting the extent of said relative movement.
16. In a machine of the character described, a pattern comprising a plurality of rules, each rule including a single group of character representations, means for spacing the rules a predetermined 35 distance apart, means for moving a plurality of groups of rules relatively, and means for limiting the extent of said relative movement.
17. In a machine of the character described, a pattern comprising a plurality of rules, each rule including character representations separately movable so that any one of the same may be projected a predetermined distance beyond the 40 surface of the pattern, manually operable means for moving said character representations, and means for spacing a plurality of groups of rules to extend over a predetermined space.
18. In a machine of the character described, a pattern comprising a plurality of rules, each rule including character representations separately 45 movable so that any one of the same may be projected a predetermined distance beyond the surface of the pattern, manually operable means for moving said character representations, means for moving a plurality of groups of rules relatively, and means for limiting the extent of said relative movement.
19. In a machine of the character described, a pattern comprising a plurality of rules, each rule including character representations separately 50 movable so that any one of the same may be projected a predetermined distance beyond the surface of the pattern, means for spacing the rules a predetermined distance apart, manually operable means for moving said character representations, and means for spacing a plurality of groups of rules to extend over a predetermined space.
20. In a machine of the character described, a pattern comprising a plurality of rules, each rule including character representations separately movable so that any one of the same may be projected a predetermined distance beyond the surface of the pattern, means for spacing the rules a predetermined distance apart, manually operable means for moving said character representations, means for moving a plurality of groups of rules relatively, and means for limiting the extent of said relative movement.
21. In a machine of the character described, a pattern comprising a plurality of rules, each rule including character representations separately movable so that any one of the same may be projected a predetermined distance beyond the surface of the pattern, means for spacing the rules a predetermined distance apart, manually operable means for moving said character representations, means for spacing a plurality of groups of rules to extend over a predetermined space, and means operable when said manually operable means is actuated for operating said means for spacing the rules a predetermined distance apart.
22. In a machine of the character described, a pattern comprising a plurality of rules, each rule including character representations separately movable so that any one of the same may be projected a predetermined distance beyond the surface of the pattern, means for spacing the rules a predetermined distance apart, manually operable means for moving said character representations, means for moving a plurality of groups of rules relatively, means for limiting the extent of said relative movement, and means operable when said manually operable means is actuated for operating said means for spacing the rules a predetermined distance apart.
23. In a machine of the character described, a pattern comprising a plurality of rules, each rule including character representations separately movable so that any one of the same may be projected beyond the surface of the pattern, means for spacing the rules to separate the character representations on adjacent rules a predetermined distance apart, manually operable means for successively moving certain of said character representations, and means rendered operable by said manually operable means for moving said pattern along a path equal to said predetermined distance.
24. In a machine of the type described, a single group of matrices having characters, means carrying an element for receiving an impression of certain of said characters, means for moving said means for carrying the impression receiving element, means including a pattern having character representations for actuating said certain characters to bring them in engagement with said element, means for arranging the character representations in the pattern in groups spaced proportional to the spacing of the groups of impressions to be produced and for spacing said character representations in said groups so that their relationship is similar to that of the impressions in said groups of impressions, and means responsive to the operation of the means for actuating said certain characters for stopping the movement of the means carrying said impression receiving element.
25. In a machine of the character described, a pattern comprising a plurality of rules, each rule including character representations separately movable so that any one of the same may be projected a predetermined distance beyond the surface of the pattern, means for spacing the rules a predetermined distance apart, manually operable means for moving said character representations, and means for spacing a plurality of groups of rules to extend over a predetermined space.

- including character representations separately movable so that any one of the same may be projected beyond the surface of the pattern, manually operable means for moving said character representations, and means for causing said character representations to move to any one of a plurality of points beyond the surface of the pattern. 5
26. In a machine of the type described, a single group of matrices having characters, means carrying an element for receiving a series of groups of impressions of certain of said characters, means for actuating said certain characters to produce said impressions including a pattern having character representations, means for arranging said character representations in said pattern in groups similar to the groups of impressions produced by said certain characters, means adapted to be actuated to space said groups of character representations, means for indicating when another group of character representations cannot be arranged in said pattern so as to cause the corresponding characters to produce an impression within a predetermined space on said element, and means for actuating said means for spacing said groups of character representations so that the groups of impressions produced by the corresponding characters will be spaced in groups extending over said predetermined space. 10
27. In a machine of the character described, a single group of matrices having characters, means carrying an element for receiving a series of groups of impressions of certain of said characters, means for actuating said certain characters to produce said impressions including a pattern having character representations, means for moving said pattern through a predetermined path, means operative as said pattern is moved through a portion of said path for arranging and spacing certain of the character representations in said pattern in groups corresponding to the arrangement and spacing of the impressions in the groups of impressions to be produced by said certain characters, and means for returning said pattern to its initial position in said portion of said path and restoring said character representations to their initial positions. 15
28. In a machine of the character described, a single group of matrices having characters, means carrying an element adapted to receive groups of impressions of certain of said characters, a member operatively connected with each of said characters and adapted to be actuated to move said character and cause it to make an impression on said element, a plurality of patterns each having character representations, means for moving said patterns along an endless path, means operative as said patterns are moved through a portion of said path for arranging said character representations in said patterns in groups similar to the desired groups of impressions to be produced whereby said arranged character representations actuate said members to cause said characters to produce said impressions as said patterns are moved through another portion of said path, means operative before said arranged character representations actuate said members for spacing said groups of character representations so that the impressions produced by said characters cor- 20
- responding to the arranged character representations in each pattern will extend over a predetermined space on said element. 25
29. In a machine of the character described, a single group of matrices having characters, means carrying an element adapted to receive groups of impressions of certain of said characters, a member operatively connected with each of said characters and adapted to be actuated to move said character and cause it to make an impression on said element, a plurality of patterns each having character representations, means for moving said patterns along an endless path, means operative as said patterns are moved through a portion of said path for arranging said character representations in said patterns in groups similar to the desired groups of impressions to be produced whereby said arranged character representations actuate said members to cause said characters to produce said impressions as said patterns are moved through another portion of said path, means operative before said arranged character representations actuate said members for spacing said groups of character representations so that the impressions produced by said characters corresponding to the arranged character representations in each pattern will extend over a predetermined space on said element, means operative as said patterns are moved through a portion of said path for arranging said character representations in said patterns in groups similar to the desired groups of impressions to be produced whereby said arranged character representations actuate said members to cause said characters to produce said impressions as said patterns are moved through another portion of said path, means operative before said arranged character representations actuate said members for spacing said groups of character representations so that the impressions produced by said characters corresponding to the arranged character representations in each pattern will extend over a predetermined space on said element, means operative after said arranged character representations have actuated said members for restoring said character representations to their initial positions. 30
30. In a machine of the type described, a single group of matrices each having a plurality of characters thereon, means carrying an element for receiving impressions of said characters, means for causing said characters to produce said impressions, means for shifting the position of said matrices relative to said means for carrying the impression receiving element so as to cause any desired character carried by the matrices to produce said impressions, a pattern having character representations, means for spacing said character representations in said pattern so that their relationship to one another is similar to that of the impressions to be produced, and means for causing said pattern to actuate said means for causing said characters to produce said impressions. 35
31. In a machine of the type described, a single group of matrices having characters, means carrying an element for receiving a series of groups of impressions of certain of said characters, a pattern having character representations arranged in groups therein spaced similar to the groups of impressions to be produced and in each of which groups the character representations are spaced so that their relationship is similar to that of the impressions in said groups of impressions, means for moving said pattern through a predetermined path, means actuated by said arranged character representations for causing said characters successively to produce said impressions as said pattern is moved through said path, and means for causing said element to move successively through paths proportional to the spaces between said character representations. 40

HENRY BEETLE HOUGH.

145
